Attorney:

UNITED STATES PATENT OFFICE

HOWARD W. PARTLOW, OF UTICA, NEW YORK

AUTOMATIC FIRE EXTINGUISHER

Application filed December 5, 1927. Serial No. 237,887.

This invention relates to automatic fire extinguishers, and the primary object thereof is to provide air compressing means which is normally maintained inactive, and which upon predetermined rise in temperature, is automatically rendered active to cause air to be compressed and conveyed to a pressure responsive release mechanism of the fire extinguisher, so as to render the latter operative.

The invention further aims to provide a device of this character, which is positive and certain in operation, which is simple and reliable, and which instantly responds, upon about normal rise in temperature.

I attain these objects by the means set forth in the detailed description which follows, and as illustrated by the accompanying drawings, in which—

20 Figure 1 is a diagrammatic view, showing the tiltable container and the local device set ready for operation by a plurality of connected actuators. Fig. 2 is a front side elevation of the local device of Fig. 1. Fig. 3 is a similar view, with the cover removed, showing the internal and external operating parts. Fig. 4 is a central vertical section on line 4-4 of Fig. 3, showing the internal parts set. Fig. 5 is a side elevation of the 25 lever that supports the container. Fig. 6 is a top plan view and partial horizontal section of one of the actuators, showing the thermostats and means for tripping the pneumatic parts. Fig. 7 is a front side elevation 30 of the same. Fig. 8 is a broken side elevation of the local device, showing the external levers interlocked in the "set" position. And Fig. 9 is a top plan view of the lever of Fig. 5.

In the drawing, 2 represents an ordinary 40 cylindrical container which is charged with the fire extinguishing chemicals, 2' is the removable head, and 2^a the usual flexible hose by which the chemicals are discharged. The container 2 is preferably pivotally mounted 45 in an upright frame 3 in such manner that its head tends to gravitate, as shown in Fig. 1, this tilting action being required in order to effect the combining of the chemicals, so as to cause them to discharge by their own 50 pressure.

The means for holding the container in the upright or "set" position, consists of a local mechanism, comprising a box 4, which may be supported by the frame 3, and having one open side which is closed by a cover 4'. Inside the box a circular diaphragm 5 is disposed concentric to a cavity 4^a formed in the bottom 4^b, the diaphragm being held in place by a cap 5' and screws 5^a. The cap 5 is formed with a concentric concave that faces the diaphragm and with a central opening 5^c, in which is loosely disposed a post 6, whose free end normally rests upon the diaphragm, the opposite end of the post being rigid in the free end of a lever 6', the latter being pivotally supported near its opposite end by a shaft 6^a that passes through the side walls of the box. A spring 6^b disposed between lever 6' and the cover 4' tends to hold the post 6 against the diaphragm 5. 7 represents a similar lever that alines with lever 6' and is supported by a shaft 7', which is journaled in the opposite walls of the box, one end thereof extending beyond the box. The free end of lever 7 is formed with a lip 7^a, which normally slightly overlaps the corresponding end of lever 6', when the mechanism is "set", as in Figs. 1, 2, 3, 4 and 8. The diaphragm is flexed by air or other fluid pressure, which enters the bottom 4^b via a passage 4^c, to which an air conductor, as α , may connect. Upon one of the outer sides of box 4 is mounted a gravitational lever 8, which is normally disposed horizontally, one of its ends being pivoted by a screw 8', its opposite end projecting beyond the cover 4' and being forked, as at 8^a. Between the ends of lever 8 is pivoted a leg 8^c, whose free end 8^d is pointed. Lever 8 is supported, when the device is "set", by a rockable trip-lever 9, which is rigid on shaft 7' and is therefore movable with lever 7. The free end of lever 9 is formed with an angular crotch 9', which receives the point 8^d of leg 8^c and prevents accidental gravitation of the latter lever. The forked end of lever 8 supports the container 2 in the inoperative position by means of a chain or other flexible part 10, that is secured to the head 2' and has a ball-end 10' that loosely engages the fork 8^a. The sudden inflation of cham-

ber 4^a, rocks the lever 6' in the direction for abruptly breaking the contact with the lip 7^a, and lever 7 is free to rock away from the bottom 4^b. This freeing of lever 7 enables the weight of the container to instantly swing lever 8 downwardly sufficiently to cause the detachment of chain 10 from the fork 8^a, and the consequent gravitation of the container towards the discharge position, shown by dotted lines in Fig. 1. By this downward movement of lever 8, the leg 8^c rocks the levers 9 and 7 towards the release position shown in Fig. 8. The leg 8^c is held in engagement with lever 9 by a spring 8^e, which enables the leg to restore said lever to the "set" position when lever 8 is again raised by the tension of spring 6^b.

The actuator of the local device 4 comprises a base 12, which is formed with perforated lugs 12^a—12^a that support respectively an air-pump or compressor 13 and a thermal unit comprising a tube 14, and a similar but smaller tube 14', which passes through the tube 14 and the lug 12^a. The pump 13 comprises a cylinder 13', having a closed end 13^a which is formed with a threaded hub 13^b that passes through lug 12^a and is held rigidly by a nut 13^c. The opposite end of cylinder 13' is closed by a screw cap 13^d. The compression of the air is effected by a cup-like plunger 15, which reciprocates in the cylinder, the compression stroke of the plunger being effected by a stout spring 16, which is disposed between the plunger and cap 13^d (see Fig. 6). The release stroke of the plunger is effected by a rod 15', which is moved outwardly for contracting spring 16 by a manually controlled bell-crank lever 17. The inner end of rod 15' comprises a ball 15^a, which is loosely seated in a socket 15^b, said socket being formed in an integral boss 15^c, and said socket being closed and the ball held from escape therefrom by a threaded bushing 15^d, which is bored out to allow rod 15' to wobble freely. Lever 17 is pivotally supported by a post 18, which is mounted upon a plate 18', the latter being clamped to the cap 13^d by a bushing 18^a which screws into a central opening of cap 13^d and serves as a loose guide for the rod 15'. In Fig. 6 the plunger 15 and related parts are disposed in readiness to compress the air in the bottom of cylinder 13' upon the release of the lever 17, the latter being held in the "set" position by a rockable lever 19, which is pivoted at 19' to a post 19^a that rises from the base 12. The lever 19 is formed at one end with a lip 19^c, which normally slightly overlaps the angular free end of lever 17, the said ends being held in contact by a guard 17' carried by the lever 17. A handle 17^a enables the operator to readily manipulate and set the lever 17. The opposite end 19^d of lever 19 is formed angular and this end is arranged to normally overlap the free end of another lever 20. When these

three levers are interlocked, the plunger 15 is restrained from compressing the air until lever 20 is swung clear of lever 19, as shown in Fig. 6. The sudden inward movement of plunger 15 sends a quick and strong blast of air from cylinder 13' via the tube α into chamber 4^a of box 4, and effects the tripping of lever 8 and the releasing of the container 2, as explained. When the contact of levers 19 and 20 is broken, the tension of spring 16 supplemented by a light spring 19^e swings lever 19 downwardly and allows lever 17 to rock on the pivot 18 to whatever extent may be determined.

The lever 20 is pivoted near its opposite end to a post 21, which is supported by lug 12^a of the base, and is rocked in the direction for breaking the contact with lever 19 directly by the thermostat 14', which is movable axially in the lug 12^a, and whose projecting enlarged end 14^b is pivoted to the short end of lever 20 (see Figs. 1, 6 and 7). The tube 14 is supported mainly by lug 12^a supplemented by a cage-like guard comprising a head 22 and a plurality of parallel rods 22', which extend between the head and lug 12^a. When the thermostat 14 expands it is movable axially in the head 22. The member 14' extends beyond the free end of tube 14 and is threaded and fitted with nuts 14^c, which are in constant engagement with tube 14, and by which said member and lever 20 may be suitably adjusted, for predetermining different abnormal temperatures by which the plunger 15 may be operated (see graduations of free end of lever 20). By this arrangement, the linear expansion of the tube 14 alone, owing to its engagement with nuts 14^c, moves the member 14' in the direction for breaking the contact of lever 20 with lever 19. A spring 20' tends to hold lever 20 in the normal or "set" position. The thermostats 14—14' are preferably made of tubing of similar metal having substantially the same expansibility. The tube 14 is preferably perforated, as at 14^a, for enabling the heat in the vicinity of the actuator to gradually affect the tube 14'. By this arrangement, when the temperature in a room rises slowly, both thermostats expand very nearly to the same extent, so that the elongation of one thermostat practically equals that of the other, with the result that lever 20 remains stationary, and the accidental or untimely release of levers 19 and 17 is forestalled. But when the temperature rises suddenly, 10° to 15°, within a minute, for example, the tube 14 expands instantly and causes tube 14' to move axially for rocking lever 20 away from lever 19, as described. Owing to the relatively high tension of the air that remains in line α between cylinder 13' and diaphragm 5, following the operation of the actuator for releasing the container 2, the forked lever 8 and lever 9 cannot be immediately locked in the "set" position for 130

supporting the recharged container, until the operator has first set lever 17 for withdrawing the plunger 15, as shown in Fig. 6. This resetting of the plunger rarefies the air in chamber 4^a, relaxes the diaphragm 5, and enables spring 6^b to effect the interlocking of lever 6' with lever 7, as shown in Figs. 1, 4 and 8.

Any suitable number of the actuators or 10 distant controls may be installed in different parts of a building, to protect several hazards or risks, and these actuators may be connected, preferably by separate conductors α to a common local device that controls the main 15 extinguishing unit, as shown in Fig. 1.

Having thus described my invention, what I claim, is—

1. A device for operating a pressure responsive release mechanism of a fire extinguisher comprising an air pump including a cylinder, a spring pressed piston in the cylinder having a rod connected thereto and extending without the cylinder, a lever pivoted to the rod to move the piston against the 25 tension of its spring, releasable means to hold said lever against movement; heat responsive means to actuate said lever holding means to release the lever, and means to conduct air compressed by the piston to said pressure responsive release mechanism to operate same.

2. A device for operating a pressure responsive release mechanism of a fire extinguisher comprising an air gun having tensioned means to compress air, means to hold 35 said compressing means under tension, temperature responsive means to release said holding means, and means to conduct air compressed in the gun to said pressure responsive release mechanism to operate the latter.

3. A device for operating a pressure responsive release mechanism of a fire extinguisher, comprising an air gun having air compressing means therein, means to actuate 45 said compressing means, means to conduct air compressed in the gun to said pressure responsive release mechanism, and temperature responsive means to effect operation of the actuating means of the gun.

50 4. A fire extinguisher operating device including air compressing means, means to normally maintain said air compressing means inactive, means to conduct compressed air from the compressing means to said pressure responsive release mechanism, and temperature responsive means to render active the said means which retains the air compressing means inactive.

60 In testimony whereof I affix my signature.
HOWARD W. PARTLOW.
